E. C. VAN DIEST ET AL

SYSTEM OF LIGHTNING PROTECTION

Filed Aug. 6, 1921

UNITED STATES PATENT OFFICE.

EDMOND C. VAN DIEST AND FRANCIS GILPIN, OF COLORADO SPRINGS, COLORADO.

SYSTEM OF LIGHTNING PROTECTION.

Application filed August 6, 1921. Serial No. 490,275.

This invention relates to a method and apparatus for the protection of buildings, tanks and other structures against lightning, and its primary object is to provide a protective medium of simple and highly efficient construction which if properly applied to a tank or other elevated structure will, during electrical storms, prevent the formation of flashes, commonly known as lightning, in the region over the protected area and thereby prevent the destruction of life and property.

We attain this object by causing a diffusion of the ground currents induced during electrical storms through the medium of a multitude of points of discharge above the protective area which prevent the concentration of electricity necessary to produce a disruptive lightning discharge.

It is well known that the lightning flashes which are most destructive to life and property are those caused by a sudden discharge of electricity between an electrified cloud and the earth. The cloud is composed of finely divided particles of vapor, each particle acting as a carrier of the electric energy latent in the atmosphere and when the vapor becomes sufficiently dense it is precipitated as rain and the electric energy carried by the vapor particles becomes concentrated and induces a similar concentration of electricity of opposite polarity on the surface of the earth.

The discharge between these forces when so concentrated as to disrupt the intervening medium causes the flash or bolt of lightning which by fire alone destroys, annually, property to an aggregate of millions of dollars.

The lightning flashes occurring during electric storms are thus directly caused by the concentration of induced ground currents, most frequently in elevated objects such as a knoll, tower, building, tank or tree, while the electric current in the cloud is diffused by distribution through the countless particles of moisture of which it is composed and it will be evident that if the induced ground current is prevented from concentrating by immediate diffusion, no flash of lightning can occur.

It is upon this principle that our invention is based and it is carried into effect by covering the area to be protected by a mul-

titude of intercommunicating upright points which either singly or collectively are connected with the ground. The number of points required to fully protect the building or other structure to which the system is applied, is proportioned to the degree of conductivity of the structure, it being essential that the conductive properties of the structure should be offset by the protective medium with a large factor of safety.

Although as stated before, the electrically communicating points may be separately connected to the ground, it is preferable to connect them collectively through the medium of a common metallic conductor of electricity since by these means a collector of induced current is provided on all sides of the protected structure, which will most directly cause its diffusion through the instrumentality of the electrically connected points.

While we do not desire to limit ourselves to the use of any specific mechanical device for carrying our improved method of lightning prevention into practice, we preferably employ as a conductive supporting medium for the ramifying points, a metallic ribbon which with a minimum of material provides a large conductive surface area and a degree of flexibility which greatly facilitates its application to structures of different forms and dimensions.

In order to fully protect a structure of extensive area, the ribbons may be interconnected in a net work which covers the surface and is connected with the ground at different sides thereof and since it is essential that the points extend in a substantially upright position, we have provided a simple fastening means which permits of their adjustment on the metallic ribbon according to the angle of the surface to which the latter is applied.

The points and their supporting media may be made of any suitable conductive material, it being preferred to use copper or an inferior material coated with copper or other noncorrosive and conductive substance.

The ribbons may be insulated from the structure to which the system is applied, by any suitable means although this is not essential if the material of the structure has a lesser degree of conductivity, and when the surface to which the net work of point

carrying conductors is applied, slopes to an apex, the points are preferably spaced closer together as they approach the highest point, since it is well known that the induced 5 ground currents tend to concentrate at the most elevated portion of an object.

An embodiment of our invention has been illustrated in the accompanying drawings in the various views of which like parts are 10 similarly designated, and in which—

Figure 1 is a side elevation of an oil tank to which our improved protective system is applied;

Figure 2, a fragmentary plan view of the 15 same;

Figure 3, a vertical section through an oil tank to which our invention is applied showing the use of an auxiliary protective device to prevent ignition of its contents by 20 accidental sparks;

Figure 4, a vertical section through an oil tank, illustrating a modification in the method of applying our invention thereto;

Figure 5, an enlarged sectional elevation 25 of one of the current diffusing points and the conductive support thereof;

Figure 6, a fragmentary section along the line 6—6, Figure 5, and

Figure 7, a fragmentary enlarged view of 30 one of the ribbons showing the spacing of the points thereon.

Referring to the drawings, the reference character 5 designates a tank of a type used for the storage of oils or other inflammable 35 liquids, which is supported in an upright position on a suitable foundation and which is covered by a relatively flat and conical roof.

The protective system of our invention 40 comprises a number of ribbon shaped conductors 3 which radiate from a central hub plate 7. The net work is arranged to adequately cover the roof of the tank and its radiating members are bent downwardly at 45 the peripheral edge of the same to extend along the upright surface of the structure for their connection with the ground.

The points 8 which extend vertically from the portions of the conductor on the roof 50 of the tank are spaced progressively further apart as they near the peripheral edge thereof, as best shown in Figure 7, and they are erected upon the conductors through the medium of sockets 6 which are fastened there- 55 to by solder or other suitable expedient.

The openings of the sockets are elongated to permit of the adjustment of the points to an upright position should the surface on 60 which the ribbon rests be out of the horizontal, and the points are secured in the sockets by solder inserted into the cavities thereof.

The points consist of short metallic rods 65 provided with a sharp tapering end and the ground connection between the downwardly extending portions of the point-supporting

radiating ribbons is preferably established through the medium of a metallic ring 10 to which each is connected and which is preferably embedded in the ground around the foundation of the structure to which the system is applied.

The conductors have been shown in the drawings as being separated from the surface of the tank through the medium of interposed blocks 12 of nonconductive material, but it will be understood that in case the structure to which the system is applied is a poor conductor of electricity, these insulations may be omitted.

In this connection it will be observed that 80 under certain advantageous conditions, the ribbons may be entirely omitted and the points applied directly to the roof of the metallic structure, as illustrated in Figure 4 of the drawings.

It will be apparent that in the event of an electrical storm the induced ground current is diffused by the multitude of electrically intercommunicating and ground-connected points and that the concentration 90 necessary to produce a flash of lightning is thereby prevented. It follows that where the points are applied in sufficient quantities to offset the electric conductivity of the structure with a fair degree of safety, no 95 electrical flashes can occur over the protected area and that our invention provides a positive protection against the detrimental effects of electrical storms by preventing any disruptive discharge of electricity between the 100 electrified cloud and the earth.

In Figure 3 of the drawings is shown an auxiliary device to prevent the contents of a tank to which our invention is applied from 105 accidentally be thrown off from the points or conductors during electrical storms.

The device consists of a chamber 13 formed above the roof of the tank by an extension of the circumferential wall thereof, 110 and a second roof which is spaced from the other. The chamber has in the center of its roof an opening covered with a fine mesh screen 14 and similarly covered openings 15 may be formed in its upright wall.

Inflammable gases arising from the combustible contents of the tank and escaping through leaky rivet holes or other apertures caused by imperfect joints between the parts of which the structure is composed, are upon entering the chamber, partially dissipated through the openings in its sides, but the greater portion of the gases escapes through the meshes of the screen which covers the opening in the roof.

In the event of a spark being thrown off any of the points of the protective medium which in this case is placed to cover the roof of the chamber, the possible ignition of the gases will occur above the screen 14 and are 130

there consumed. The screen thus acts as a burner for the gases arising from the chamber and the flames are prevented from reaching the contents of the tank in any 5 manner whatsoever.

The chamber thus provides a protective medium which will effectively prevent conflagrations such as frequently occur by lightning or other causes, and we desire it 10 understood that if so desired the chamber may be used without the current diffusing element within the scope of our invention.

When the tank is used without the superposed chamber, the screen-covered opening 15 can be formed directly in the roof thereof, to concentrate accumulated gases to one foraminated outlet which as before, acts as a burner for their consumption outside the tank in case of fire.

20 The outlet whether in the roof of the tank or in the roof of the chamber is obviously placed so as not to be obstructed by the conductive supports of the lightning protector and when the supports are arranged to radiate from a central point, the outlet may 25 be divided into sections arranged between the supports.

The screen-covered outlet or outlets if 30 formed in the roof of the tank are furthermore advantageous in that they prevent accumulation of gases and thereby reduce the chances of conflagration in case of fire by sparks emitted from the points of the lightning protector or other causes. Inasmuch 35 as the construction and arrangement of the outlet or outlets in the roof of the tank is similar to those of the outlet or outlets in the roof of the chamber, as shown in Figure 3, no separate illustration of this feature 40 of the invention is required to convey a complete understanding of its purpose and advantages.

What we claim and desire to secure by Letters-Patent is:

1. In a system for protecting structures 45 from lightning, a plurality of conductive radial arms, and vertically disposed conductive points protruding from the upper surface of each of said radial arms, the said points being arranged in continuous rows 50 and spaced in such manner that the distance between the successive points of each row decreases as the center is approached.

2. A system for protecting structures from lightning, comprising a central member, 55 a plurality of conductive radial arms disposed about said central member, and vertically disposed conductive points protruding from the upper surface of said central member and of each of said radial arms, 60 the said points being arranged in continuous rows and spaced in such manner that the distance between the successive points of each row decreases as the center is approached. 65

3. A system for protecting structures from lightning, comprising a central hub plate, a plurality of conductive radial arms disposed about said hub plate, uprights integral with said radial arms, the lower ends 70 of which are adapted to be grounded, a common metallic strip engaging said lower ends, and vertically disposed conductive points protruding from the upper surface of each of said radial arms, the said points 75 being arranged in continuous rows and spaced in such manner that the distance between the successive points of each row decreases as the center is approached.

In testimony whereof we have affixed our 80 signatures.

EDMOND C. VAN DIEST.
FRANCIS GILPIN.
